UNITED STATES PATENT OFFICE.

WILLIAM W. McELRATH, OF LOUISVILLE, KENTUCKY.

BUCKET FOR ROTARY PUMPS.

Application filed November 25, 1924. Serial No. 752,257.

The present invention relates to bucket construction as applied to rotary pumps, and the like.

The primary object of my invention is to provide a bucket construction adapted to create high vacuum in rotary pumps and discharge the fluid handled therein with the least possible effort.

Another object of my invention is to provide an improved bucket construction for rotary pumps which will permit high performance over a wide range of operation.

A further object of my invention is to provide a bucket construction for rotary pumps which will tend to follow the contour of the casing reactionary of the fluid while in operation.

A still further object of my invention is to provide a bucket construction for rotary pumps adapted to follow the casing reactionary of the fluid impact, and discharge said fluid from the bucket by centrifugal force during the cycle of operation.

A much sought object of my invention is to provide a bucket construction for rotary pumps adapted to improve the volumetric efficiency thereof during operation.

The above and other objects in view, I shall in the following specification bring out more complete details, and in which,

Fig. 1 represents an end elevated view of the conventional rotary pump with the head removed, and wherein is shown buckets of my construction.

Fig. 2 represents a cross-sectional view of Fig. 1 taken on line 1—1 showing the relation of casing, rotating element, and intake opening as well as discharge.

Fig. 3 represents a plan bottom view of one of the buckets showing openings and blade contour.

Fig. 4 represents a cross-sectional projected view of Fig. 3 taken on line III—III.

Referring more particularly to the drawings, and in which case like numerals are used to designate like parts throughout the specification, and first in which Fig. 1 is shown to be a conventional design of rotary pump mounted on a base, the casing of which is designated by numeral 1. In this casing is mounted a rotating element 2 on a shaft 3 and secured thereto by a key 4. The periphery of said rotating element 2 has disposed at intervals buckets 5—5—5—5 as shown, so arranged that they are adapted to swing out against the casing during rotation of the

shaft 3. In the casing 1 is formed an inlet opening designated by numeral 10 and diametrically opposite is a discharge opening designated by numeral 11. These openings are more clearly shown in Fig. 2.

The buckets 5—5—5—5 as shown have an opening 6 which is adapted to receive the fluid entering the pump intake 10 and in the construction of the bucket is formed another opening 8 separated from opening 6 by an interposed blade 7. This construction is best shown by referring more particularly to Figs. 3 and 4. It is clearly noted that the blade 7 extends vertically and forwardly so as to form what might be called a "leading blade" while at the rear of the bucket is the "following blade" designated by numeral 9. The leading blade 7 is shown to be of a curvature such as would cause the following blade 9 to swing outwardly against the casing 1 when being rotated in a fluid such as oils, gasolines, varnishes, water, and other liquids. This reaction is caused by the impact of the liquid as is known to the art.

It is also desirable to discharge the fluid from the buckets with as little effort as possible, this is done by allowing the entrapped fluid to be discharged through opening 8 and if the pump is operating at high speed the fluid will pass out this opening by centrifugal force as is known characteristically of this design of centrifugal pumps.

In considering the operation of the conventional design of rotary pump with my invention as disclosed herein may say that the pump as shown in Fig. 1 is adapted to rotate counter-clockwise the bucket 5 passing over inlet opening 10 exhaust the air partially therefrom until sufficient suction is established to draw the fluid into the casing 1 at this point. The fluid coming first into contact with the leading blade 7 causes a bucket reaction which forces following blade 9 against the casing 1 tightly enough to insure high vacuum the fluid thus entrapped revolves with the rotating element 2 until it reaches the discharge opening 11 where it is discharged by the difference of relative displacement. Should the pump be operating at high speed the fluid will pass out of opening 8 in the bucket due to relative shape and high velocity. I have experimented with various types of rotary pumps in which the buckets themselves were supposed to swing outwardly by centrifugal force, but found them very inefficient at low speeds. In my

design of bucket construction I find quite a difference as the fluid impinging on the leading blade 7 aids considerably at low speeds, and at high speeds the discharge of the fluid 5 through opening 8 seems to relieve a chocked condition owing to its design and the rapid discharge of the fluid under high velocity.

With the foregoing I think that nothing else need be said relative to my invention 10 other than I desire it to be understood that various changes and operating conditions may be employed, and limitation is only made by the spirit of the appended claim.

What I claim and desire to secure by Letters Patent, is:

In a rotary pump, a stationary casing, a rotatable member mounted in the casing and having peripheral pockets therein opening toward the wall of the casing, and a bucket

hinged at one side in each of said pockets, 20 each of said buckets comprising a pair of side walls provided intermediate their ends with a curved loading blade extending generally in the direction toward the center of the rotary member and having between said side walls and at the outer ends thereof a follower blade spaced from the loading blade and having its inner surface curved in divergent relation to the curvature of the loading blade, 25 said loading blade providing an intake opening at its inner side and an outer opening between the loading and following blades, said following blade adapted to receive impact of fluid in the outer opening and adapted for contact with the peripheral wall of the casing. 30

In testimony whereof I affix my signature.

WILLIAM W. McELRATH.
